CLAIM

We claim the ornamental design for a seating unit, as shown and described.

DESCRIPTION

FIG. 1 is a front perspective view of a seating unit according to a first embodiment;

FIG. 2 is a rear perspective view of the seating unit of FIG. 1;

FIG. 3 is a front view of the seating unit of FIG. 1;

FIG. 4 is a rear view of the seating unit of FIG. 1;

FIG. 5 is a side view of the seating unit of FIG. 1;

FIG. 6 is a top view of the seating unit of FIG. 1;

FIG. 7 is a bottom view of the seating unit of FIG. 1;

FIG. 8 is a front perspective view of a seating unit, according to a second embodiment;

FIG. 9 is a rear perspective view of the seating unit of FIG. 8;

FIG. 10 is a front view of the seating unit of FIG. 8;

FIG. 11 is a rear view of the seating unit of FIG. 8;

FIG. 12 is a side view of the seating unit of FIG. 8;

FIG. 13 is a top view of the seating unit of FIG. 8; and,

FIG. 14 is a bottom view of the seating unit of FIG. 8.

The dashed lines and broken lines are for purposes of illustrating environmental structure and form no part of the claimed design.
